Primary Examiner — Patricia Palasik(74) *Attorney, Agent, or Firm* — Volpe and Koenig, P.C.**CLAIM**

The ornamental design for an induction apparatus, as shown and described.

DESCRIPTION

FIG. 1 is a front elevational view of an induction apparatus in accordance with my design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom view thereof;

FIG. 7 is a top, front, right perspective view thereof; and,

FIG. 8 is a top, right, rear perspective view thereof.
